UNITED STATES PATENT OFFICE

KENNETH E. MC CONNAUGHEY, OF INDIANAPOLIS, INDIANA

PAVING MACHINE AND PROCESS

Application filed January 19, 1928, Serial No. 247,778. Renewed October 6, 1930.

My invention is concerned with the construction of highway pavements, particularly of the bituminous type, and it is my object to provide a process and means whereby a satisfactory pavement may be laid without excessive expense. More specifically, it is my object to provide a process and means for paving which will eliminate all unnecessary handling of material and which will avoid the necessity for expensive mixers and other apparatus.

I accomplish my objects by mixing the aggregate and bituminous binder on the surface being paved desirably by drawing over such surface a road grading machine having one or more oblique blades which will serve to move the loose aggregate transversely of the road and mix it thoroughly with the binder. This road grader or maintainer is desirably provided with means for discharging on the material moved by the blade or blades a suitable bituminous binder which becomes thoroughly mixed with the aggregate as it is moved along the blades by their passage over the surface.

The accompanying drawing illustrates an apparatus embodying my invention: Fig. 1 is a plan view of a road maintainer to which my invention is applied; Fig. 2 is a vertical transverse section through the road maintainer on the line 2—2 of Fig. 1; Fig. 3 is a vertical section on the line 3—3 of Fig. 2; Fig. 4 is a horizontal section through the hollow distributing member through which the liquid binder is supplied to pipes extending over the blades; and Fig. 5 is a vertical longitudinal section through one of the binder-distributing pipes showing a discharge nozzle.

The road maintainer illustrated in the accompanying drawing is one which I have found desirable for use in carrying out my process. It embodies a frame 10 the rear end of which is supported on vertically adjustable wheels 11 and the front end of which is connected through a draw bar 12 to a tractor 13. On the under side of this frame are mounted a forward pair of rearwardly converging scraper blades 14, a pair of rearwardly diverging scraper blades 15, a rear pair of

rearwardly converging blades 16, and a distributing blade 17. The rear ends of the front pair of rearwardly converging blades 14 are spaced apart to provide for the passage of material between them to the rearwardly diverging blades 15. The rear pair of rearwardly diverging blades 16 project outwardly beyond the rear ends of the blades 15 in order that they may receive material discharged from such blades. Like the front pair of rearwardly diverging blades 14, the rear pair of rearwardly converging blades 16 are spaced apart at their inner ends in order to permit the passage of material to the distributing blade 17. This distributing blade 17 may be set obliquely at an angle to or directly across the frames 10. By suitable adjustment of the rear wheels 11 and draw-bar 12, the height of the blades may be varied at will.

This maintainer which has just been described is merely illustrative of one type of road working machine in which my invention may be embodied. While I prefer to employ a road machine having a plurality of blades in order that I may secure a thorough agitation of the aggregate in one passage of the machine, such a maintainer is not necessary, as my invention may be applied to a machine having but a single blade.

For the purpose of supplying the liquid bituminous binder which is to be mixed with the aggregate on the road surface, I provide a supply tank 20. This tank 20 is conveniently, although not necessarily, mounted upon a separate vehicle 21; as such equipment is usually available in the construction of roads, it being used for the purpose of distributing the bituminous binder at desired points. Liquid binder from the tank 20 is conveyed to the vicinity of the blade or blades of the road machine in order that it may be discharged onto the aggregate being moved by such blades. If the tank 20 is carried by a vehicle separate from the road machine itself, I attach to it a flexible conduit 22 through which the binder may be conveyed to the road machine.

In the machine illustrated in the drawing, the flexible conduit 22 connects with a hollow

distributing member 23 mounted on the road machine desirably at the junction of the two rearwardly diverging blades 15. From this distributing member 23 there radiate outward respectively over the two pairs of blades 14 and 15 distributing pipes 24 which are provided at intervals with discharge nozzles 25 arranged to discharge in a general downward direction. If desirable the frame 6 10 may be provided with brackets 26 for supporting the outer ends of the pipes 24. Each of the pipes 24 is rotatable in its associated bracket 26 and in the distributing member 23 in order that the nozzles 25 may be arranged to discharge either ahead of or in 15 rear of their associated blade as is clear from Fig. 3.

In applying my pavement by my improved process, I first grade the road to the desired 20 cross-section, if it is not already in that condition. A road scraper or maintainer is then passed over the road with its blade or blades set to remove material usually to a depth of approximately two inches. The exact depth 25 of material removed, however, is not important, and may be varied to suit the circumstances. The material scraped from the road is usually discharged to one side or the other of the road machine 30 and is left in windrows extending longitudinally of the road. During this operation, the pipe or pipes 24 are adjusted to discharge onto the road base behind their associated blades in order to impregnate the scraped 35 surface with the bituminous binder. After a stretch of road of the desired length has been thus treated, I rotate the pipes 24 so that they discharge in advance of their respective blades. I adjust the road machine 40 so that the blades are barely in contact with the surface of the road, and I pass the machine along the road. In this passage of the 45 machine along the road, the windrows of surface material left by the preceding step are engaged by the rearwardly converging blades 14, and material is moved over the road base inward along such blades and outward along the rearwardly diverging blades 15. During its passage along these blades, 50 it is being sprayed with bituminous binder discharged from the pipes 24, and this binder is thoroughly worked into the aggregate as it passes along the blades. After being discharged from the rearwardly diverging 55 blades 15, the impregnated aggregate is picked up by the blades 16 and thereby given further agitation and mixing. From the blades 16, the material is discharged to the distributing blade 17 which may be set either 60 obliquely as indicated in full lines in Fig. 1 to leave the aggregate in windrows adapted to be further mixed and agitated or perpendicular to the frame 10 as indicated in dotted lines to distribute the treated aggregate over 65 the road surface in a layer of even thickness.

If the aggregate is not sufficiently mixed with the binder by one passage of the road machine, it may be re-worked in the manner just described; and after the final working, it is distributed evenly over the road surface by 70 setting the distributing blade 17 transversely of the frame 10.

After the treated aggregate is evenly distributed, it is rolled in the usual manner. If additional depth of pavement is desired, 75 the required amount of aggregate may be placed upon the road, impregnated with binder and evenly distributed as above outlined, and then rolled.

I claim as my invention:—

1. A paving machine, comprising a frame adapted to be moved over the surface to be paved, a scraper blade carried by said frame and disposed obliquely to the direction of frame movement, and a conduit located above and substantially parallel to said blade and adapted to be supplied with a liquid bituminous binder, said conduit having one or more discharge openings arranged to discharge generally downwardly, said conduit being rotatable about its axis to direct the discharge from said discharge openings either ahead of or behind said blade. 80

2. A paving machine, comprising a frame adapted to be moved over the surface to be paved, a scraper blade carried by said frame and disposed obliquely to the direction of frame movement, and a conduit located above and substantially parallel to said blade and adapted to be supplied with a liquid bituminous binder, said conduit having one or more discharge openings arranged to discharge generally downwardly, said conduit being adjustable to direct the discharge from said discharge openings either ahead of or behind 95 said blade. 100

3. A paving machine, comprising a frame adapted to be moved over the surface to be paved, a scraper blade carried by said frame and disposed obliquely to the direction of frame movement, and conducting means having discharge openings and adapted to be supplied with a liquid bituminous binder, said conducting means being adjustable to discharge either ahead of or behind said blade. 110 115

4. A paving machine, comprising a frame adapted to be moved over the surface to be paved, a scraper blade carried by said frame and disposed obliquely to the direction of frame movement, and means for discharging a liquid bituminous binder either ahead of or behind said blade. 120

5. A paving machine, comprising a frame adapted to be moved over the surface to be paved, a plurality of oblique scraper blades carried by said frame and arranged to move loose material back and forth transversely to the direction of frame movement, and means associated with each of said blades for 125

discharging liquid bituminous binder either ahead of or behind it.

6. A paving machine, comprising a frame adapted to be moved over the surface to be paved, a pair of forwardly diverging scraper blades carried by said frame, a pair of rearwardly diverging scraper blades arranged to receive loose material discharged from said forwardly diverging blades, a hollow member adapted to be supplied with a liquid bituminous binder, and a plurality of pipes radiating from said hollow member and disposed respectively above said blades, each of said pipes being provided with one or more lateral discharge openings and being rotatable in said hollow member whereby it can be arranged to discharge either ahead or behind its associated blade.

7. A paving machine, comprising a frame adapted to be moved over the surface to be paved, a blade carried by said frame and disposed obliquely to the direction of frame movement, whereby loose material on the surface to be paved may be moved transversely to the direction of frame movement, and means for discharging a liquid bituminous binder on such loose material as it is moved transversely by said blade.

8. A paving machine, comprising a frame adapted to be moved over the surface to be paved, a ground-engaging scraper blade carried by said frame, means for holding said scraper blade in fixed vertical position relative to said frame and means mounted on said frame for discharging a liquid bituminous binder on the scraped road surface behind said blade.

9. The process of applying a bituminous pavement to a road surface, comprising loosening the material of the road surface to a predetermined depth and disposing the material thus loosened in windrows extending longitudinally of the road, applying bituminous binder to the road base, moving the loosened material back and forth over the road base and evenly distributing it while simultaneously supplying bituminous binder thereto, and subsequently rolling such evenly distributed material.

10. The process of applying a bituminous pavement to a road surface, comprising loosening the material of the road surface to a predetermined depth and disposing the material thus loosened in windrows extending longitudinally of the road, moving the loosened material back and forth over the road base and evenly distributing it while simultaneously supplying bituminous binder thereto, and subsequently rolling such evenly distributed material.

11. The process of applying a bituminous pavement to a road surface, comprising loosening the material of the road surface to a predetermined depth and collecting the material thus loosened, applying bituminous bind-

er to the road base, moving the loosened material back and forth over the road base and evenly distributing it while simultaneously supplying bituminous binder thereto, and subsequently rolling such evenly distributed material.

12. A paving machine, comprising a frame adapted to be moved over the surface to be paved, a plurality of oppositely disposed oblique blades carried by said frame and adapted to move and work loose material on such surface and beneath said frame back and forth transversely to the direction of frame movement, and means carried by said frame for discharging a liquid bituminous binder on such loose material as said frame passes over it, whereby such binder may be intimately mixed with such loose material by the action of said blades.

13. A paving machine, comprising a frame adapted to be moved over the surface to be paved, a plurality of sets of oblique agitating blades carried by said frame and arranged one behind the other, said blades being oppositely disposed to move and work loose material on such surface back and forth transversely to the direction of frame movement, and means carried by said frame for discharging a liquid bituminous binder on such loose material in advance of the rearmost set of blades, whereby such binder may be intimately mixed with such loose material by the action of said rearmost set of blades.

14. A paving machine, comprising a frame adapted to be moved over the surface to be paved, a plurality of oblique agitating blades carried by said frame and arranged one behind the other, said blades being oppositely disposed to move and work loose material on such surface back and forth transversely to the direction of frame movement, means carried by said frame for discharging a liquid bituminous binder on such loose material in advance of the rearmost set of blades, whereby such binder may be intimately mixed with such loose material by the action of said rearmost set of blades, and an oblique distributing blade located in rear of said rearmost set of agitating blades.

15. The method of applying a bituminous pavement to a road surface, which comprises breaking up the road surface to form loose particles of aggregate continuously and repeatedly working the aggregate while moving it back and forth across the road and simultaneously spraying said aggregate with a bituminous binder.

16. The method of applying a bituminous paving composition of aggregate and a binder, which comprises continuously and repeatedly working the aggregate over the road surface while moving it back and forth transversely of the road and simultaneously spraying said aggregate with a bituminous binder.

17. In a device for treating with liquefied

bitumen a supply of aggregate moving through the device, comprising a series of members arranged to engage the aggregate, said members being disposed oppositely obliquely to the general direction of aggregate movement to work the aggregate, and means for discharging bitumen on such aggregate as it is being worked by said members.

10 18. In a device for treating with liquefied bitumen a supply of aggregate moving through the device, comprising means for discharging bitumen on the aggregate, and a series of members arranged to engage the aggregate, said members being disposed oppositely obliquely to the general direction of aggregate movement to work the aggregate and mix the bitumen with it.

15 19. A process of treating aggregate with liquefied bitumen, comprising moving aggregate on a supporting surface, repeatedly changing the direction of aggregate movement to work and agitate it, and simultaneously spraying bitumen on the aggregate so that it may become thoroughly mixed therewith as the aggregate is worked and agitated.

20 In witness whereof, I have hereunto set my hand at Indianapolis, Indiana, this 17th day
25 of January, A. D. one thousand nine hundred and twenty eight.

KENNETH E. McCONNAUGHAY.
